[57] CLAIM

The ornamental design for a construction game element, as shown and described.

DESCRIPTION

FIG. 1 is a perspective view of the construction game element of the present invention;

FIG. 2 is a rear view of the construction game element of the present invention;

FIG. 3 is a top view of the construction game element of the present invention;

FIG. 4 is a front view of the construction game element of the present invention;

FIG. 5 is a bottom view of the construction game element of the present invention;

FIG. 6 is a side view of the construction game element of the present invention;

FIG. 7 is an opposite side view of the construction game element of the present invention;

FIG. 8 is a perspective view of an alternate extended embodiment of the construction game element of the present invention;

FIG. 9 is a rear view of the alternate extended embodiment of the construction game element of the present invention;

FIG. 10 is a top view of the alternate extended embodiment of the construction game element of the present invention;

FIG. 11 is a front view of the alternate extended embodiment of the construction game element of the present invention;

FIG. 12 is a bottom view of the alternate extended embodiment of the construction game element of the present invention;

FIG. 13 is a side view of the alternate extended embodiment of the construction game element of the present invention; and,

FIG. 14 is an opposite side view of the alternate extended embodiment of the construction game element of the present invention.
